(57) **CLAIM**

The ornamental design for a flex section in shaft for ENT instrument, as shown and described.

DESCRIPTION

FIG. 1 is a front right perspective view of a flex section in shaft for ENT instrument, showing our new design; FIG. 2 is a front elevational view of FIG. 1, with the rear elevational view being a mirror image thereof;

FIG. 3 is a right side elevational view thereof, with the left side elevational view being a mirror image thereof; FIG. 4 is a top plan view thereof; and,

FIG. 5 is a bottom plan view thereof.

The spaced cuts shown in evenly spaced broken lines in FIGS. 1 and 3-5 are unclaimed environment and form no part of the claimed design. The dashed-dot broken lines in FIGS. 1 and 3-5 define the bounds of the claimed design, and form no part of the claimed design.
